[57] **CLAIM**

The ornamental design for an anti-lift unit for windshield wipers, as shown and described.

DESCRIPTION

FIG. 1 is a top perspective view of an anti-lift unit for windshield wipers showing my new design on a reduced scale;

FIG. 2 is a top plan view thereof;

FIG. 3 is a bottom plan view thereof;

FIG. 4 is a side elevational view of one side thereof;

FIG. 5 is a side elevational view of the other side thereof;

FIG. 6 is a fragmentary side elevational view thereof, taken in the direction of the arrow 6 in FIG. 2;

FIG. 7 is a front elevational view thereof; and,

FIG. 8 is a rear elevational view thereof.

FIG. 1

FIG. 2

FIG. 3

FIG. 4

FIG. 5

FIG. 6

FIG. 7

FIG. 8
